UNITED STATES PATENT OFFICE.

ALBERT CHARLES GOWING AND MILLARD COLE SPENCER, OF WORCESTER, MASSACHUSETTS.

LOOSE-COUPLED TUNING-COIL.

1,083,085.

Specification of Letters Patent. Patented Dec. 30, 1913.

Application filed June 21, 1912. Serial No. 705,034.

To all whom it may concern:

Be it known that we, ALBERT C. GOWING and MILLARD C. SPENCER, both citizens of the United States, and residents of Worcester, in the county of Worcester and State of Massachusetts, have invented a new and Improved Loose-Coupled Tuning-Coil, of which the following is a full, clear, and exact description.

10 Our invention relates to a tuning coil of the loose coupled type to be used in wireless telegraphy and other arts involving the propagation of electric waves through space.

It consists of primary and secondary 15 windings, the primary comprising two sections which can be independently adjusted with regard to each other, and the secondary likewise comprising two sections which are capable of independent adjustment, so that 20 the self-inductance of both the primary and secondary windings can be regulated at will, and, at the same time, the mutual inductive effect of one winding upon the other can also be controlled with the utmost nicety.

25 Reference is to be had to the accompanying drawings, forming a part of this specification, in which similar characters of reference indicate corresponding parts in all the figures, and in which—

30 Figure 1 is a front elevation of our improved tuning coil; Fig. 2 is a vertical sectional view on the line 2—2 of Fig. 1, and Fig. 3 is a view showing an arrangement of 35 circuits to illustrate how our tuning coil can be changed from the loose coupled to the close coupled type, so that it may be used for "listening in" on any wireless outfit in use.

Referring particularly to the drawings, 40 the numeral 1 represents a supporting rod carried upon standards 2 having bearings 3. This rod is preferably fixed in the bearings 3, so as to hold the same against rotation and on the same are mounted a plurality of 45 rings shown at 4, 5, 6 and 7. The last-named ring, 7, is preferably fixed on the supporting rod 1, the other three rings being rotatably mounted upon the same, so that they can be shifted through any angular distance.

50 Each of the rings is not cylindrical in shape, but preferably the outer faces of the same are concentrically curved around the rod 1 as a center, making said rings similar to the spherical zone in shape. As shown in 55 Fig. 1, the rod on which these rings are

mounted is diametrically located with respect to each of them and passes through the body of each ring at opposite points. Around the rings 4 and 5 are wound the sections constituting the portions of the primary winding, the ring 4 receiving turns forming one primary section and the ring 5 receiving a like number of turns forming the other primary section, these two sections being connected in series. The ring 6 likewise receives a number of turns to form one section of the secondary and the ring 7 receives the other section of the secondary, the two sections being connected together in series the same as the case of the primary 60 winding. The primary windings are indicated as a whole by the numeral 8 and the secondary windings by the numeral 9. On account of the fact that the rings 4, 5 and 6 can be rotated around the rod 1 as an axis 65 independently of one another, every possible position of adjustment can be obtained.

It is well known that in electric-wave work, the length of the wave in the circuit bears a certain relation to the inductance 80 of the same, and in tuning, the inductance of the receiving circuit must be regulated before any message can be received. This is ordinarily done by cutting out a plurality 85 of turns of the inductance coil, but with our invention we vary the inductance of the primary circuit by changing the angle at which the rings 4 and 5 are arranged to each other. When the rings lie in the same plane but oppose one another, the self-inductance is at a minimum, and, in effect, a non-inductive winding is secured. When the rings 4 and 5 are turned to move through 90 one hundred and eighty degrees with respect to each other, so that they no longer oppose each other, the inductance is brought up to the maximum. The same effect is obtained with the secondary sections on the rings 6 and 7, and the coefficient of coupling of the tuner, that is, the mutual inductive effect of the primary upon the secondary winding is varied and controlled by turning the primary at any required angle 95 to the secondary. The advantage of this improved form of tuner is that there are no sliding contacts along the wire as in the ordinary variable inductance tuning coil, also, all of the wire in our tuner is in use all 100 of the time. There are no turns which are cut out of the coil, and thus the "end effect" 110

due to the inductance of the inactive coils in the ordinary tuner, is eliminated.

We also, by dispensing with the sliding contacts, eliminate the contact resistance caused by the interposition of the slider that is used with an ordinary variable inductance coil. This contact resistance consumes a large amount of energy and is a decided disadvantage. Furthermore, in the ordinary inductance coil which is operated by cutting out one or more turns, the smallest increment or decrement of inductance is a single turn of wire. With our coil the inductance can be varied from minimum to maximum by 10 infinitely small amounts depending, of course, upon the angle between the planes of the rings on which the sections of the primary and secondary windings are mounted. Furthermore, we can use stranded wire in 15 winding the coils since there are no sliding wire contacts, and the resistance to high frequency current is thus made less because the "skin" effect is eliminated, and by lessening the resistance of the primary circuit by the use of stranded wire, closer tuning 20 can readily be obtained.

The connections shown on Fig. 3 illustrate how we can change our tuner over to a close-coupled type when "listening in" is 25 to be attempted. In this view, 10 represents an aerial to which the primary turns 8 are connected in series, being grounded at 11. 12 represents a conductor in parallel with the primary turns 8 leading to a switch 13 which bridges a gap between the conductor 12 and a contact 14. From this contact 14 leads a conductor 15 to the secondary 9, and from the other end of the secondary runs a conductor 18 to a switch 19, a detector 16 and a condenser 17 being interposed in this conductor 18. The switch 19 bridges the gap to a contact 20 which is connected to the wire which grounds the primary.

It is well known that a close coupled tuner is better adapted for picking up stations on account of the fact that it is less selective than a loose coupled one; hence, the use of both close and loose coupled coils may be done away with by the use with our tuner 45 of a circuit such as shown in Fig. 3, to enable either the loose coupled or the close coupled effect to be obtained. When the switch is in the position shown in Fig. 3, the sections of the primary and secondary windings are connected in loose coupled relation; when the switch is moved to the dotted-lined position, the coils are in close coupled relation, and in this latter position, the operator can 50 "listen in" whenever he desires. Any convenient or preferred mechanism may be connected to the movable rings 4, 5 and 6, so that they may be turned at will according to the degree of adjustment required and held in any desired position.

Having thus described our invention, we 65 claim as new and desire to secure by Letters Patent:

1. In an improvement of the kind described, the combination of four concentric rings, a rod upon which said rings are mounted, said rod being diametrically located with respect to said rings, one of said rings being affixed to said rod and the remainder of said rings being rotatable with respect thereto, a section of wire wound 75 upon each outer face of two of said movable rings, said sections being connected in series to form a primary circuit, and a section of wire wound upon the outer face of each of the remaining rings and connected 80 in series to form a secondary circuit, the adjustment of the movable rings around the rod serving to vary the self-inductive effect of the windings and the coupling of the primary and the secondary. 85

2. In an improvement of the kind described, the combination of four concentric rings, a rod upon which said rings are mounted, said rod being diametrically located with respect to said rings, the innermost of said rings being affixed to said rod and the remainder of said rings being rotatable with respect thereto, a section of wire wound upon each outer face of two of said movable rings, said sections being connected 95 in series to form a primary circuit, and a section of wire wound upon the outer face of each of the remaining rings and connected in series to form a secondary circuit, the adjustment of the movable rings around the rod serving to vary the self-inductive effect of the windings and the coupling of the primary and the secondary. 100

3. In an improvement of the kind described, the combination of four concentric rings, a rod upon which said rings are mounted, said rod being diametrically located with respect to said rings, the innermost of said rings being fixed to the rod and the remainder of the rings being adjustable 110 with respect thereto, a section of wire wound upon the outer face of the inner two of said movable rings, said sections being connected in series to form a primary circuit, and a section of wire wound upon the outer face of each of the two remaining rings and connected in series to form a secondary circuit, the adjustment of the movable rings around the rod serving to vary the self-inductive effect of the windings and the coupling of 115 the primary and the secondary. 120

4. In an improvement of the kind described, the combination of a plurality of rings, a rod upon which said rings are mounted, one of said rings being fixed to 125 the rod and the remainder of said rings being rotatable thereon, a section of wire mounted upon each of some of the movable

rings and connected together to form a primary circuit, and a section of wire wound upon each of the remainder of said rings and connected to form a secondary circuit, 5 the adjustment of the movable rings around the rod serving to vary the inductive effect of the windings and the coupling of the primary and secondary.

5. In an improvement of the kind described, the combination of a plurality of concentric rings, a rod upon which said rings are mounted, the innermost of said rings being fixed to the rod and the remainder of said rings movable thereon, a 10 section of wire wound upon each of some of said rings and connected to form a primary circuit, and a section of wire wound upon each of the remainder of the rings and connected to form a secondary circuit, the adjustment of said rings serving to vary the 15

self-inductive effect of the windings and the coupling of the primary and secondary.

6. In a tuning coil, the combination of a plurality of rings, primary windings each mounted upon one of said rings, said primary windings being connected in series with each other, secondary windings mounted upon others of said rings, said secondary windings being in series with each other, and a rod extending diametrically through each 25 of said rings for facilitating the rotation of any of said rings relatively to the others.

In testimony whereof we have signed our names to this specification in the presence of two subscribing witnesses.

ALBERT CHARLES GOWING.
MILLARD COLE SPENCER.
